US00D958764S

(12) **United States Design Patent** (10) **Patent No.:** **US D958,764 S**
Rokkam et al. (45) **Date of Patent:** **** Jul. 26, 2022**

(54) **HIGHER TEMPERATURE VENTED SUSCEPTOR**

(71) Applicant: **ASM IP HOLDING B.V.**, Almere (NL)

(72) Inventors: **Uday Kiran Rokkam**, San Diego, CA (US); **Sam Kim**, Chandler, AZ (US); **Saket Rathi**, Tempe, AZ (US); **Dakai Bian**, Tempe, AZ (US)

(73) Assignee: **ASM IP HOLDING B.V.**, Almere (NL)

(**) Term: **15 Years**

(21) Appl. No.: **29/782,159**

(22) Filed: **May 4, 2021**

Related U.S. Application Data

(62) Division of application No. 29/677,173, filed on Jan. 7, 2019, now Pat. No. Des. 920,936.

(57) **CLAIM**

The ornamental design for a higher temperature vented susceptor, as shown and described.

DESCRIPTION

FIG. 1 is a front perspective view of a higher temperature vented susceptor, showing our new design;

FIG. 2 is a back perspective view thereof;

FIG. 3 is a left side view thereof; and,

FIG. 4 is a right side view thereof.

The dash-dash lines in FIGS. 1-4 form no part of the claimed design.

1 Claim, 3 Drawing Sheets
